Patented Aug. 31, 1971

221,651

DRILL PIPE PROTECTOR

Mason W. Napper, Morgan City, La., assignor to Galaxie Manufacturing and Sales, Inc., Morgan City, La.

Filed Nov. 17, 1969, Ser. No. 20,115

Term of patent 14 years

Int. Cl. D23—01

U.S. Cl. D23—47

FIG. 1

FIG. 2

FIG. 3

FIG. 1 is a front perspective view of a drill pipe protector embodying my new design;

FIG. 2 is a rear perspective view thereof; and

FIG. 3 is a top plan view thereof.

I claim:

The ornamental design for a drill pipe protector, substantially as shown.
